WAX SWEATING

Vanderveer Voorhees, Hammond, Ind., assignor
to Standard Oil Company, Chicago, Ill., a cor-
poration of Indiana

Application January 13, 1934, Serial No. 706,514

8 Claims. (Cl. 196—20)

This invention relates to a process of separating oils from waxes and particularly for separating petroleum oils from paraffin wax by an improved sweating process.

In the refining of paraffin wax, it is common practice to chill the lubricating oil distillate fractions and filter the paraffin therefrom, thereby producing a wax cake. This cake which may originally contain about 50% of wax, is then melted and charged into a large tank known as a sweating oven where the temperature is lowered by means of water circulated through closed pipe coils in order to solidify the wax. Warm water is then circulated through the coils and the temperature gradually raised until the wax begins to sweat, the sweat oil being drawn off, leaving the oil-free wax in the oven. By the use of this process it has been difficult to make a sharp separation between the oil and the wax; there was either a loss of considerable wax in the drips or a retention of considerable oil in the wax product. An object of the present invention is to obtain more accurate and uniform temperature control in the sweating oven, both during the period of wax solidification and during the sweating operation with the result that larger yields of drier wax are obtained than has been heretofore possible. Another object of the invention is to economize on the heat required for carrying out the operation.

The invention may be readily understood by referring to the accompanying drawings which form a part of this specification and wherein:

Figure 1 shows an elevational view partially in section of a simple form including only two sweating ovens.

Figure 2 shows a cross section of a sweating oven, and Figure 3 shows a layout for an indefinite number of sweating ovens with pipe connections.

Referring to Figure 1, a sweating oven 10 consists of a vertical cylindrical tank containing trays 11 with suitable outlets for the drips 12 leading to manifold 13 and outlet valve 14. Cooling and heating of the wax charge is effected by passing a low-boiling liquid or vapor through suitable pipes 15 which are shown in cross section in Figure 2. These pipes pass vertically through the oven and are manifolded into top manifold 16 and bottom manifold 17. The construction of the other sweating oven 18 is substantially identical. A pump 19 is connected between the lower manifolds of the two ovens and a compressor 20 is connected between the upper manifolds of the two ovens.

The operation of the process is substantially as follows: Melted wax, containing a considerable amount of oil, for example, 50%, may be charged into the oven 10 through the charging valve 21. When the oven has been fully charged a suitable low-boiling liquid is forced by pump 19 through valves 22 and 23 into the header 17 and heat exchange tubes 15. The liquid vaporizes in these tubes and the vapors are passed by headers 16 through valve 36 and by-pass line 37 to the inlet of compressor 20, thence through valve 25, line 29 and valve 28 to header 16a, valves 24 and 27 being closed, in oven 18. Oven 18, being already charged with solidified wax, is gradually heated by condensation of the vapors in the coils therein and the condensed vapors returned to the lower header 17a and are recycled through valves 26 and pump 19. The operation is continued until all the wax in oven 10 has been solidified. As the temperature in oven 10 falls and the temperature in oven 18 rises, it becomes necessary to establish a continually increasing pressure differential between headers 16 and 16a by means of compressor 20. At the beginning of the operation, however, the pressure of the vapors in header 16 will be greater than the pressure in header 16a and at that stage it is not necessary to operate compressor 20. As long as that condition prevails the compressor 20 is cut out by closing valves 25 and 27 and regulating the rate of flow of the vapors by means of valve 28 in by-pass line 29. Similarly when compressor 20 is operating it may be unnecessary to use pump 19 and valves 23 and 31 may be opened or a storage tank or collector may be connected in the system at this point.

When all the wax in oven 10 is solidified the direction of flow of the liquid is reversed by resetting the valves on the by-passes around pump 19. Valves 23 and 26 are closed and valves 30 and 31 are opened, permitting liquid to flow from header 17 through by-pass line 32 to the inlet of pump 19, then through valve 22 and by-pass line 33 to header 17a. Vapors are allowed to enter the header 16 under sufficient pressure to condense in the oven 10 and thereby cause the oil and low melting wax to liquefy and flow from the oven through the drip line 13 as previously described. After the sweating has proceeded to a sufficient point substantially all the oil is removed from the wax, the valve in drip line 13 is closed and the remaining wax in the sweater is allowed to melt, either by increasing the pressure on the vapors in the heating pipes 15 or by ad-

mitting live steam directly to the oven through steam line 35. The melted wax is withdrawn from drain outlet 10A and also from drip line 13 by opening valve 14, the melted wax being directed to a separate receptacle from the drips. Wax is withdrawn from oven 18 in the same manner, live steam being admitted at connection 35A and wax being withdrawn from the drain line 18A and drip line 14A. The vapor flow between headers 16 and 16a is conveniently reversed by closing valves 28 and 36 and opening valves 24, 25 and 27.

Instead of using only two ovens in the process, I may employ a series of ovens connected as shown in Figure 3. The ovens are designated by the letters A, B, C, D, E and F. A suitable heat transfer liquid is contained in tank 50 and may be transferred by pump 51 and line 52 to header 53 connected with the lower point of the heat exchange coils in each oven. The vapors in each oven pass through header 54 from one oven to the other or they may be returned by lines 55A, 55B, 55C, 55D, 55E and 55F to header 56 and compressor 57 where they are compressed 25 and condensed in condenser 58, returning them to the storage tank 50. The vapors may also be passed from manifold 54 by compressor 59 and manifold 60 to any other desired oven through connections 61A—B—C, etc., in which case compressor 57 may be shunted.

In operation the process may be conducted as follows: Oven A may be freshly charged with melted wax at a temperature of 150-200° F.; oven B may be cooling; the wax in oven C may be solidified and ready for the sweating operation; oven D may be undergoing sweating; oven E may be also undergoing sweating; and oven F may be discharging sweated wax. The cooling liquid may be passing through pump 51, lines 52 and manifold 53 through lines 62, valve 63 and into the coil in oven B. The vapor from this oven may pass by valve 64B to manifold 54 and compressor 59 to manifold 60 and thence into the heat exchange coil in sweating ovens D and E through lines 64D and 64E, valves 64D, 64E, 66D and 66E being closed. The liquid condensing in ovens D and E flows by gravity through lines 62D and 62E back to liquid manifold 53. If at any time there is more vapor collecting in the system 50 than is needed for sweating it may be withdrawn from any oven at will through lines 55A, B, etc., to vapor header 56 and pump 57 where it is condensed in condenser 58 and returned to the liquid storage.

In view of the fact that the temperature in oven E will be higher than that in oven D, which is at an earlier stage of the sweating cycle, it is possible to employ vapor at different pressures for these ovens. For example, vapor for oven D 60 may be led directly from one other oven, for example, oven B, which is cooling through line 55B and manifold 56, thence through line 55D and into sweater D. At the same time vapor from oven C, which is completing the cooling cycle, 65 may pass by valve 64C, through manifold 54 and compressor 59, to manifold 60 and thence through line 64E to oven E, valves 64E and 66E being closed. The temperature obtained in the oven is a direct function of the pressure applied to the vapor and this can be controlled in any way desired by the operation of variable compressor 59 and by proper control of valves.

The next stage of the process above outlined 75 is the charging of oven F with fresh stock and

the cooling of oven A which has just been charged. On introducing cooling liquid to oven A, which may be at a temperature of 150-200° F. for example, the vapor pressure generated may be very considerable. The rate of evaporation of the liquid in any heat exchange coil is controlled by maintaining a back pressure on the valves 64A and 66A, in order to keep the cooling coil submerged and avoid local cooling at the bottom of the oven. The vapors which are withdrawn at 10 the higher pressure are suitable for use directly in sweating another oven at a somewhat lower temperature, thus avoiding the necessity of re-compression. When the cooling has proceeded to the stage where the vapor pressure is no longer 15 sufficient to effect sweating in the other oven the vapors may then be boosted in pressure or diverted to a different oven which is at a lower temperature. By routing the vapors in this manner a maximum economy can be obtained with 20 a minimum cost for both heat and compression. Under some conditions of operation it may be desirable to employ a separate refrigerating liquid charging pump for each oven, this pump being suitably located in line 62A, B, C, etc. 25

As a suitable heat exchange fluid I may use propane, butane, pentane, hexane, methyl and ethyl ethers, methyl chloride, sulfur dioxide, etc. In selecting a suitable cooling fluid it is desirable that the boiling point of the liquid be below the 30 freezing point of the wax undergoing sweating. In the case of paraffin wax this temperature is about 70-80° F. However, higher boiling liquids might be employed if a vacuum were used to bring about their evaporation. This is undesirable on 35 account of the increased cost of handling the larger volumes of vapors entailed by this operation. It is also important that the heat exchange liquid have a fairly definite boiling point, i. e., that its boiling range be within a very few degrees 40 in order that more accurate temperature control can be obtained and fractionation be avoided. The liquid which I prefer to use is butane whose boiling point is 1° C. at ordinary pressure. By maintaining a moderate pressure on the system 45 the boiling point of the butane can be regulated to any desired degree.

One of the advantages of the process is that extremely uniform cooling and heating are obtained because of the close relationship between 50 the boiling point and condensing point of the liquid and vapors and the pressure which is imposed thereon. Thus, a large sweating oven containing several hundred barrels of wax can be cooled at substantially uniform rate throughout 55 the entire oven, as long as the coils are interiorly submerged with cooling liquid. Likewise, during sweating exactly the same temperature will prevail in every part of the oven which is in contact with condensing vapors. In this operation 60 it is necessary, of course, to remove condensed vapors as rapidly as the condensate is formed. This is a decided improvement over previous practice using water for cooling and heating in which case the temperature gradient from the 65 bottom to the top of the oven will usually be 10° F. or more. The reason for this high gradient is the necessity of transferring all the heat by changing the temperature of the water, whereas in the present process, the heat transferred is 70 the latent heat of vaporization and condensation, no change in temperature being involved. The gradient from the top to the bottom of the oven in this case is well below 10° F. and usually below 5° F. 75

Although I have described my invention with respect to a specific embodiment thereof, the scope of the invention is intended to be limited only by the following claims:

5 1. I claim:

1. The method of removing oils from waxes, which comprises solidifying an oil wax mixture, liquefying the oil without liquefying the wax in said mixture by condensing a vaporized material 10 which is normally a gas at the sweating temperature employed, in heat exchange relation to all parts of said solidified oil wax mixture whereby uniform and readily controllable temperatures are obtained throughout the body of solidified oil 15 wax mixture and withdrawing the liquefied oil from the solidified wax.

2. The method of uniformly controlling crystallization and melting of wax mixed with oil in a sweating oven which comprises introducing into the heat exchange coil disposed throughout the interior of said oven a working fluid having a boiling point, under the pressure conditions existing within said coil, close to the melting point of the wax-oil mixture, and regulating the pressure on the working fluid so as to produce a change of state of the working fluid thereby producing a material change in heat content of the wax-oil mixture sufficient to bring about the desired change, with only minor change in temperature.

3. The method of regulating the exchange of heat in a wax sweating system employing a plurality of sweating ovens, which comprises vaporizing a refrigerant in heat exchange relation with a liquid oil wax mixture contained in a sweating oven whereby the mixture is uniformly solidified and condensing the vapors from said sweating oven in indirect heat exchange relation to a solidified oil wax mixture in another sweating oven, whereby the temperature is raised gradually and uniformly and the oil and low melting wax are sweated from the high melting wax with minimum liquefaction of the latter.

4. In apparatus of the class described, a sweating oven, a plurality of trays in said oven, a pair of manifolds, a plurality of heat exchange pipes connected between said manifolds and arranged in heat exchange relation to said trays, means for introducing or withdrawing a liquefied refrigerant into or out of one of said manifolds, means for withdrawing or introducing vapors from or into the other manifold, means for controlling the pressure within said heat exchange pipes whereby liquid refrigerant introduced into one manifold, may be evaporated and discharged as vapor from the other manifold, or vapor introduced into one manifold may be condensed and discharged as liquid from the other manifold and means for withdrawing from said trays the liquid products of the sweating operation.

5. In apparatus of the class described, a plurality of sweating ovens, means for supporting a solidified oil wax mixture in said sweating ovens, a pair of manifolds associated with each sweating oven, heat exchange means in each 5 sweating oven connected with both manifolds and in heat exchange relation to said oil wax supporting means, whereby either a refrigerant liquid may be introduced through one manifold, vaporized in said heat exchange means and withdrawn through the other manifold or whereby refrigerant vapors may be introduced through one manifold liquefied in said heat exchange means and withdrawn through the other and means for circulating a refrigerant, whereby it 10 is vaporized in one sweating oven to solidify an oil wax mixture and condensed in another oven to cause the sweating of the oil from the wax 15 therein.

6. In apparatus of the class described, a plurality of sweating ovens, means for obtaining uniform heating and cooling in each of said sweating ovens by the condensation and vaporization, respectively, of refrigerants therein, a low pressure manifold, a high pressure manifold, a compressor 25 for withdrawing vapors from the low pressure manifold and compressing them into the high pressure manifold, means for selectively connecting the top of each of said sweating ovens with the high or low pressure manifolds, a manifold 30 connected to the base of each sweating oven for introducing liquefied refrigerant into the ovens or withdrawing condensed refrigerant from the ovens and means for condensing and storing 35 plus refrigerant liquid.

7. The method of gradually and uniformly increasing the temperature throughout all parts of a wax sweating oven equipped with coils or other indirect heat exchange means disposed throughout the interior thereof, which comprises supplying to said heat exchange means vapors of a liquid at a pressure equal to or slightly above the condensing pressure corresponding to the temperature prevailing in the oven at any particular moment and withdrawing condensed vapors from 45 said heat exchanging surfaces.

8. The process of gradually and uniformly reducing the temperature of a sweating oven equipped with coils or other indirect heat exchange means, comprising introducing a liquid 50 within said heat exchange means until the surfaces thereof are substantially submerged, gradually reducing the pressure of the vapors above said liquid thereby causing said liquid to boil at a temperature equal to or slightly below the temperature prevailing in said sweating oven at the moment and continuously withdrawing the vapors evolved from said liquid.
